United States Patent Office.

JEARUM ATKINS, OF MOKENA, ILLINOIS.

Letters Patent No. 74,656, dated February 18, 1868.

IMPROVEMENT IN SAFETY-VALVES.

The Schedule referred to in these Letters Patent and making part of the same.

TO WHOM IT MAY CONCERN:

Be it known that I, JEARUM ATKINS, of Mokena, Will county, in the State of Illinois, have made new and useful Improvements in "Safety-Valve Regulators;" and I hereby declare the following to be a full and exact description of the same, reference being had to the drawings that accompany and form a part of these specifications.

Figure 1 is an elevation of the spring-balance and lever, and a vertical section of the valve and its seat.

Figure 2 is a front view of the standard and its attachments.

Figure 3 is a horizontal section on a line *a b*.

Figure 4, another mode of applying a rolling fulcrum to levers of safety-valves.

Figure 5, sectional view on a line *c d*.

Figure 6, still another mode of applying my device.

Figure 7, sectional view on a line *e f*.

Letter A, the safety-valve and its seat, attached to the top of the boiler, are similar to those in common use, and need no particular description. The spindle B connects the safety-valve with the spring-balance lever C in the usual manner, excepting that the pin *e*, which connects the spindle with the lever, is V-shaped, to make the bearing upon a single line to avoid friction. The spring-balance, D, is made in the usual form, but differs from those in use in the mode of attaching it to the boiler and the lever C, the outer end of which forms an arc of a circle, whose centre is at the centre of rocking-bar *k*. The upper end of the spindle E of the spring-balance has a mortise, through which the lever C passes, a friction-roller, *f*, being placed over said lever in the mortise. A spring-catch, *h*, attached to the spindle E, takes into notches on the under side of the lever C, and serves to hold the spring-balance in whatever position it may be placed. A screw, *i*, attached to the lower end of the spring-balance, passes through a short rocking-bar, *k*, which is pivoted to brackets attached to the boiler-front by screw-bolts, as seen at *l l*, fig. 1. A nut, *m*, that works on the screw *i*, is for the purpose of giving the spring-balance the proper degree of tension. The right-hand or inner portion of the lever C is bent up perpendicularly, forming a right angle with the other portion of said lever. The hole, in which a pin, *n*, at its angular point works, is elongated perpendicularly, to allow the lever to rise or fall a little, while the pin *n* remains stationary in the standard *P*, to prevent any lateral motion in lever C. The standard *P* has a large mortise in it, the lower portion of which is contracted to the thickness of the lever C, as seen at *r* in fig. 2. In the mortise referred to, is placed the link *S*, which connects the lever C with the top of the standard; the link receiving the upward strain on the inner or right-hand end of lever C, the pin *n*, as before stated, being only to prevent lateral motion in the lever. The lower end of the link *S* is slotted, and receives the end of lever C, and is attached to it by the V-shaped pin *t*, and to the standard at the top by a similar pin, *u*. The pins *e*, *t*, and *u*, being V-shaped; the friction upon them is avoided, consequently there will be but little difference between the pressure of steam that will lift the valve and that at which it will descend to its seat.

The spring-balance, in ordinary working, will stand in a vertical position, as shown in fig. 1, when the pressure of steam will be at its maximum; but whenever it is desirable to adjust the spring-balance, so that steam will escape at a reduced pressure, it is only necessary to move the spindle E, on the lever C, towards the valve, thus shortening the leverage; consequently the pressure at which steam will escape is correspondingly diminished. A graduated scale may be marked on the lever C to indicate the pressure at which steam will escape, and by which the spring-balance may be set, so that steam will escape at any point desired. When the safety-valve is closed, the point of bearing on the three pins, *n*, *t*, and *u*, will all be on the same vertical line, and the point at which the upward strain is received on the short end of lever C will be at the centre of pin *n*, or on the vertical line *d d*; but when the lever C is lifted by the pressure of steam upon the valve, the perpendicular portion of said lever is inclined to the right. The link *S* is also inclined to the right, and the point on lever C, at which the strain is sustained, being at a point on a line extended horizontally through the bearing of pin *e*, at which a line extended through pins *t* and *u*, falls.

It will be seen that when the lever C rises by the pressure of the escaping steam, the short end of lever C is lengthened, which will compensate for the increasing tension of the spring-balance, and that by increasing the length of the vertical part of lever C, or by diminishing the length of link *S*, or by both, a point will be

reached at which the lengthening of the short arm of lever C, by the lifting of the valve, as described, will compensate for the increasing stiffness of the spring-balance, and also the clogging or jamming of the safety-valve, so that no material increase in the pressure of steam will take place above that at which it commences to escape from the valve.

I have also illustrated two other modes of applying a rolling fulcrum to the levers of safety-valves, one mode being shown in fig. 4, and the other in fig. 6. In both of these latter plans it will be seen, by reference to the drawings, that I contemplate applying the rolling fulcrum to the short end of the holding-down lever, instead of the long end, as described in the foregoing specifications. In fig. 4, C represents the lever. A horizontal bar, G, lying on the top of lever C, has a slot at one end, in which are placed three rollers, H, all of the same diameter, held by the pin v, as seen in fig. 5. It will also be seen that the centre roller bears upon lever C, and receives the upward pressure of said lever, while the two outside rollers bear against the top of the mortise in the standard I, a recess being formed in the top of the mortise, over the centre roller, to prevent its bearing against the standard. An angular lever, J, having its fulcrum at the top of standard K, is for the purpose of giving motion to the rollers H. The outer portion of the lever C is turned upward, and forms the segment of a circle, T. There are several notches along the outer curved surface of this segment, into which the spring-catch L takes, to hold the lever J in its position. As the lever J is moved up and down, the rollers H roll back and forth on lever C, and has the effect of lengthening and shortening the leverage, by which means the apparatus may be adjusted so that steam will escape at any desired pressure. Again, referring to fig. 6, the holding-down lever is represented at C; a single roller, R, is carried in the slotted end of the angular lever M; a rounded shoulder at the angle of the lever bears against the top of the mortise in standard X. Several teeth, projecting above the shoulder, fit into mortises in the top of the standard to hold the lever in position. An upright standard, Y, is attached to the front of the boiler, the upper portion of which forms a segment of a circle, whose centre is at the angular point of lever M. This standard passes through a mortise in the outer end of lever C, and is for the purpose of guiding lever M in its up-and-down movements, the spring-catch being used to hold the lever at any point desired, as in the mode last described. By moving the handle of lever M up or down, the roller is carried backward or forward on lever C, thus changing the leverage for the purposes heretofore explained.

What I claim, and desire to secure by Letters Patent, is—

1. The construction of the safety-valve lever C, or its equivalent, with its outer portion curved, and its combination with the mortised spindle B, roller f, and spring-catch h, substantially as specified.
2. In combination with a spring-balance D, I claim the rocking-bar k, screw i, and nut m, as described and set forth.
3. I claim the arrangement of the lever C, bent to form an angle with the link S, standard P, and pins n, t, and u, substantially as described.
4. I also claim the combination of the rolling fulcrum f with the safety-valve lever C, substantially as shown and described.

In testimony whereof, I have signed my name to this specification in the presence of two subscribing witnesses.

JEARUM ATKINS.
